UNITED STATES PATENT OFFICE

141,490

DESIGN FOR A COMBINED CALENDAR, LETTER OPENER, AND RULER

Robert Vantassel Henderson, Toronto, Ontario,
Canada

Application February 12, 1945, Serial No. 117,897

Term of patent 14 years

(Cl. D74—5)

To all whom it may concern:

Be it known that I, Robert Vantassel Henderson, a British subject, residing at the city of Toronto, in the county of York, Province of Ontario, Dominion of Canada, have invented a new, original, and ornamental Design for a Combined Calendar, Letter Opener, and Ruler, of which the following is a specification, reference being had to the accompanying drawing forming part thereof.

dar, letter opener, and ruler, showing my new design; and

Figure 2 is a fragmentary view of Figure 1 showing a portion of the calendar in detail, the same being merely representative.

I claim:

The ornamental design for a combined calendar, letter opener, and ruler, as shown and described.

ROBERT VANTASSEL HENDERSON.
